CLAIM

The ornamental design for an industrial transport cart frame as shown and described.

DESCRIPTION

FIG. 1 is a perspective view of the industrial transport cart frame, shown in a configuration of use;

FIG. 2 is another perspective view of the industrial transport cart frame shown in an alternate configuration of use;

FIG. 3 is a rear perspective view of the industrial transport cart frame;

FIG. 4 is a front perspective view thereof;

FIG. 5 is a rear view thereof;

FIG. 6 is a front view thereof;

FIG. 7 is a left side view thereof;

FIG. 8 is a right side view thereof;

FIG. 9 is a top plan view thereof; and,

FIG. 10 is a bottom plan view thereof.

The broken lines in FIGS. 1 & 2 showing an industrial transport cart depict environment that form no part of the claimed design. All other broken lines depict portions of the industrial transport cart frame that form no part of the claimed design.
